ELECTRIC STEAM GENERATOR

Stanley Livingstone, Newton, Mass., assignor to
 Livingstone Engineering Company, a corpora-
 tion of Massachusetts

Application July 20, 1945, Serial No. 606,164

13 Claims. (Cl. 219—40)

1

This invention relates to electric steam generators and has for an object the provision of a generator which operates to develop steam at controlled elevated pressures rapidly, and to maintain the controlled developed pressure with a minimum of power consumption.

A further object of the invention is to provide a self-contained generator for production of steam at controlled pressures above atmospheric for platen heating and other uses.

The accompanying drawing illustrates a generator of this invention with a portion thereof shown in cross-section. The generator includes a cylindrical casing 10 provided with upper and lower closure heads 12 and 14, respectively, forming a heating chamber 16 surrounded by suitable insulation 18 and outer casing 20. An inlet pipe 22 leads into the bottom of the chamber and is connected through a liquid level gauge 24 to an injector coupling 26 permitting introduction of liquid, preferably water, into the system to bring the liquid in the heating chamber 16 to about the level shown. By the use of an injector, water may be introduced into the system while the generator is in operation at an internal pressure above that of normal water main pressure.

A steam outlet 30 leads from the upper portion of chamber 16 through head 12 and suitable connections, including a pressure gauge 32 and a safety valve 34, to a feed pipe 36 leading to a platen, not shown, or other steam consumption device to be supplied with steam. In the case of a platen, a closed circuit (not shown) is provided back to return pipe 38, as conventional in the industry.

The water or other liquid in chamber 16 is heated by an electrical heating unit which, in the form shown in the drawing, comprises three electrodes 40 suspended through insulators 42 on an electrode holder 44. Each electrode is surrounded with a cylindrical open ended tube 46. Such a unit is adapted for operation on three-phase current supplied from an external source through separate leads 48a, 48b and 48c.

The entire electrode assembly is suspended through the interposition of rod 50 from a piston 52 operating in a cylinder 62 formed by a pipe connection 60 leading through heating chamber head 12.

The electrode assembly is thus adapted for vertical movement from a position as shown, wherein the electrodes are completely immersed in the liquid in chamber 16, to elevated positions wherein the electrodes are partially or wholly elevated out of the liquid. Such movement is

2

caused by the action of the pressure in chamber 16 upon the under surface of piston 52 which is suitably packed to prevent escape of steam between the piston and walls of pipe 60.

5 In order, however, to prevent such movement prematurely, i. e. prior to development in chamber 16 of a desired elevated steam pressure, my generator includes structural features which provide opposition to the movement of piston 52 and 10 its suspended electrode holder 44 until after the desired pressure for which the generator is set has been developed. For this purpose, cylinder chamber 62 is connected to heating chamber 16 through a line 64 joining steam feed pipe 36. 15 This connection 64 thus acts to maintain the pressure in cylinder 62 equal to the pressure in heating chamber 16 during building up of steam pressure in chamber 16. Movement of piston 52 and its suspended electrode holder 44 is thus 20 opposed and prevented.

When a desired elevated steam pressure is developed, for example 60 pounds, there is no longer any necessity for utilizing full power capacity to maintain the generator (which is 25 capable of developing much higher pressures) in operation at the desired below capacity 60 pound pressure. In order then to cut down the power consumption, I include in my generator a suitable control, operating only after the generator has built up to substantially the desired operating pressure, to permit electrode holder 44 to be elevated relative to casing 10 to move electrodes 40 from the completely immersed position in which they are shown progressively to positions 30 where they are only partially immersed in the liquid. By thus reducing the electrode surface area in contact with the liquid, the power consumption is reduced.

This objective is attained by interposing, in the 35 line 64, a reducing valve 70. This valve is adjustable and is set to close at a pressure slightly below the desired operating pressure.

The differential in the setting of reducing valve 40 and the desired operating pressure will be 45 dependent upon the area of piston 52 exposed to the action of pressure in heating chamber 16 and the weight of the piston, rod, and electrode assembly. In practice, the reducing valve is adjusted to a higher or lower setting to secure the 50 desired pressure reading on gauge 32, although for any single design, it is possible to calculate the setting required for any given desired operating pressure.

Operation is as follows: 55 A suitable quantity of water having been ad-

mitted, and suitable connection of leads 48 being made to a source of three-phase current, electrodes 49 will operate to develop steam in the chamber 16. With the pipe 36 leading through a closed circuit to pipe 38, pressure will build up in the system including the cylinder 62 and no movement of the electrodes relative to the liquid level will take place because the pressure above and below piston 52 will remain equal so long as reducing valve 70 remains open. As soon, however, as the pressure has built up to the setting of reducing valve 70, as for instance slightly below 60 pounds pressure, the valve 70 closes, and thereafter operates to maintain the pressure in cylinder 62 at the pressure of the setting of valve 70, regardless of further building up of pressure in chamber 16. Pressure in chamber 16 will then continue to increase over the valve 70 setting, until it becomes sufficient, for example 60 pounds, to lift piston 52 and its suspended electrodes upwardly, overcoming the opposition of the weight of the electrode unit and the lesser pressure maintained in cylinder 62. As the electrodes 49 rise above the level of the liquid in chamber 16, the amount of power consumption progressively decreases and the action will be such that the electrodes will continue to rise until such time as the power expended will be insufficient to maintain the desired pressure, whereupon, with a drop in pressure, the maintained pressure in chamber 62 will act, with the weight of the piston and electrode unit, to return the electrodes towards a fully immersed full consumption position, and to a position where the immersed surface area of the electrodes is just sufficient to generate sufficient steam to maintain the desired pressure. Minimum power will be expended at such position.

A nice regulation of the steam pressure is thus provided to produce any desired pressure below capacity depending upon the setting of valve 70. At the start, full current consumption is continuously utilized to give rapid up-to-desired pressure build-up; reduction in current consumption does not commence until this pressure has been attained; and thereafter the device automatically adjusts itself to maintaining the pressure with a minimum of power consumption.

The reference character 80 indicates a condensate trap which acts to remove condensate from the line 64 to prevent accumulation in chamber 62. This device acts to release condensate automatically without drop in pressure in the line 64.

I claim:

1. An electric steam generator comprising a container defining a heating chamber, an electrode movable in said container from a position adapted for complete immersion in a liquid contained in a portion of said container to positions of only partial immersion therein, means responsive to progressively increasing pressure developed in said heating chamber for moving said electrode from completely immersed to partially immersed position, and control means responsive to said progressively increasing heating chamber pressures for opposing and preventing such electrode movement at any heating chamber pressure below a predetermined elevated pressure and for permitting such electrode movement at heating chamber pressures above said predetermined elevated pressure, whereby as pressure in said heating chamber builds up above said predetermined elevated pressure said electrode is moved to a partially immersed position.

2. An electric steam generator comprising a

- 5 container defining a heating chamber, an electrode movable in said container from a position adapted for complete immersion in a liquid contained in a portion of said container to positions of only partial immersion therein, means responsive to progressively increasing pressures developed in said heating chamber for moving said electrode from completely immersed to partially immersed position, and control means responsive to said progressively increasing heating chamber pressures for opposing and preventing such electrode movement at progressively increased pressures below a predetermined elevated pressure and means for terminating complete opposition of said opposing means at heating chamber pressures exceeding said predetermined elevated pressure whereby as pressure developed in said heating chamber builds up above said predetermined elevated pressure said electrode is moved to a partially immersed position.
- 10 3. An electric steam generator comprising a container defining a heating chamber, a cylinder adjacent said heating chamber, a piston in said cylinder movable towards and away from said heating chamber in response to pressures developed in said heating chamber and having its inner face exposed to the pressure prevailing in said heating chamber, an electrode extending into said heating chamber and connected to said piston, and means for maintaining the pressure in said cylinder on the outer face of said piston always at least equal to the pressure in said heating chamber as pressure builds up in said chamber to a predetermined elevated pressure.
- 15 4. An electric steam generator comprising a container defining a heating chamber, a cylinder adjacent said heating chamber, a piston in said cylinder movable towards and away from said heating chamber in response to pressures developed in said heating chamber, an electrode extending into said heating chamber and connected to said piston, means for maintaining the pressure in said cylinder always at least equal to the pressure in said heating chamber as pressure builds up in said chamber to a predetermined elevated pressure and means for maintaining the pressure in said cylinder less than the pressure in said heating chamber when the latter pressure exceeds said predetermined pressure.
- 20 5. An electric steam generator comprising a container defining a heating chamber, a cylinder adjacent said heating chamber, a piston in said cylinder having its inner face exposed to the pressure prevailing in said heating chamber and being movable away from said heating chamber in response to pressure developed in said heating chamber, an electrode extending into said heating chamber and connected to said piston, and means for progressively building up pressure in said cylinder on the outer face of said piston to a predetermined maximum elevated pressure as the pressure progressively builds up in said heating chamber, to oppose and prevent movement of said piston until said chamber pressure exceeds said maximum elevated pressure.
- 25 6. An electric steam generator comprising a container defining a heating chamber, a cylinder adjacent said heating chamber, a piston in said cylinder movable towards and away from said heating chamber in response to pressures developed in said heating chamber, an electrode extending into said heating chamber and connected to said piston, means for building up pressure in said cylinder progressively to a predetermined maximum pressure as the pressure pro-

- 60
- 65
- 70
- 75

gressively builds up in said heating chamber, to oppose and prevent movement of said piston, and means for maintaining said pressure in said cylinder less than the pressure in said heating chamber when the latter pressure exceeds said predetermined pressure.

7. An electric steam generator comprising a container defining a heating chamber, a cylinder adjacent said heating chamber, a double acting piston in said cylinder, said cylinder being connected on each side of said piston for communication with said heating chamber, whereby pressure developed in said chamber builds up equally on both sides of said piston, an electrode extending into said chamber and connected to said piston, and control means for cutting off the communication of said cylinder on the side of the piston away from said electrode with said chamber.

8. An electric steam generator comprising a container defining a heating chamber, a cylinder adjacent said heating chamber, a piston in said cylinder movable towards and away from said heating chamber progressively in response to pressures developed in said heating chamber, an electrode extending into said heating chamber and connected to said piston, a connection communicating said cylinder on the other side of said piston from said electrode with said heating chamber and a valve interposed in said communicating connection for cutting off said communication.

9. An electric steam generator comprising a container defining a heating chamber, a cylinder adjacent said heating chamber, a piston in said cylinder movable towards and away from said heating chamber progressively in response to pressures developed in said heating chamber, an electrode extending into said heating chamber and connected to said piston, a connection communicating said cylinder on the other side of said piston from said electrode with said heating chamber, and a reducing valve interposed in said communicating connection for automatically cutting off said communication when the pressure in the steam chamber exceeds a predetermined minimum pressure.

10. An electric steam generator comprising a container defining a heating chamber, a cylinder adjacent said heating chamber, a double acting piston in said cylinder, said cylinder being connected on each side of said piston for communication with said heating chamber, whereby pressure developed in said chamber builds up equally on both sides of said piston, an electrode extending into said chamber and connected to said piston, control means for cutting off the communica-

cation of said cylinder on the side of the piston away from said electrode with said chamber, and a condensate trap for releasing accumulation of condensate in said cylinder.

- 5 11. An electric steam generator comprising a container defining a heating chamber adapted to contain liquid to be vaporized, an electrode mounted for movement in said container between positions of greater and less immersion in said liquid, means for moving said electrode, and control means responsive to the pressure within said container for initiating said movement only when said pressure exceeds a predetermined elevated pressure.
- 10 12. An electric steam generator comprising a container defining a heating chamber adapted to contain liquid to be vaporized, an electrode mounted within said chamber for movement between positions of greater and less immersion in said liquid, means responsive to the pressure within said container for moving said electrode to a position of less immersion, and means responsive to the pressure within the container for preventing operation of said first means when the pressure within the container is less than a predetermined elevated pressure.
- 15 13. An electric steam generator comprising a container forming a heating chamber adapted to contain liquid to be vaporized, an electrode within said container, a piston connected to said electrode and movable to move said electrode between positions of greater and less immersion in said liquid, a cylinder for said piston having one of its head spaces in communication with the interior of said container, whereby increase of pressure within the container tends to move said electrode into a position of lesser immersion in said liquid, a conduit connecting the other head space of the cylinder with the interior of said container, and means for reducing the pressure transmitted to the piston through said conduit when the pressure within said container exceeds a predetermined value.
